CLAIM

The ornamental design for a combined wringer lever with connecting rods and housing for a roller sponge mop, as shown and described.

DESCRIPTION

FIG. 1 is a perspective view of a combined wringer lever with connecting rods and housing for a roller sponge mop showing my new design;

FIG. 2 is a front elevational view thereof;

FIG. 3 is a side elevational view thereof; and,

FIG. 4 is a rear elevational view thereof.

The broken line showing of a mop handle, sponge backing member, roller assembly, and sponge is for illustrative purposes only and forms no part of the claimed design.
